UNITED STATES PATENT OFFICE.

WILLIAM M. WEYGANT, OF CENTRAL VALLEY, NEW YORK.

DESIGN FOR A WHIP-STOCK.

SPECIFICATION forming part of Design No. 34,183, dated February 26, 1901.

Application filed December 20, 1900. Serial No. 40,592. Term of patent 7 years.

To all whom it may concern:

Be it known that I, WILLIAM M. WEYGANT, a citizen of the United States, and a resident of Central Valley, in the county of Orange and 5 State of New York, have invented and produced a new and original Design for a Whip-Stock, of which the following is a specification.

The essential features of my design consist in a whip-stock having a butt portion circular in cross-section, the said circular butt portion merging into a short portion having a pronounced taper and polygonal in cross-section, the said pronounced tapered portion in turn merging into a portion having a much less pronounced taper polygonal in cross-section and extending toward the tip.

In the accompanying drawings, Figure 1 shows the whip-stock in elevation. Fig. 2 is an enlarged view, in side elevation, of adjacent portions of the circular and polygonal

parts of the whip-stock. Fig. 3 is a section taken in the plane of the line 3 3 of Fig. 2, and Fig. 4 is a section taken in the plane of the line 4 4 of Fig. 2.

A represents the circular portion at the 25 butt of the whip-stock, a the short polygonal portion having the pronounced taper, and B the polygonal portion extending toward the tip with a less pronounced taper.

What I claim is—

The design for a whip-stock, substantially as herein shown and described.

In testimony that I claim the foregoing as my invention I have signed my name, in presence of two witnesses, this 19th day of December, 1900. 35

WILLIAM M. WEYGANT.
